[57] **CLAIM**

The ornamental design for a combined riflescope elevation adjustment knob and windage adjustment knob, as shown and described.

DESCRIPTION

FIG. 1 is a perspective view of a combined riflescope elevation adjustment knob and windage adjustment knob showing my new design, the broken lines showing the riflescope are for illustrative purposes only and form no part of the claimed design;

FIG. 2 is a side elevational view thereof; and

FIG. 3 is an opposite side elevational view thereof.

Fig. 3
